Specification of Letters Patent. Patented Mar. 21, 1916.

Application filed August 28, 1913. Serial No. 787,084.

To all whom it may concern:

Be it known that I, MORRIS F. SMITH, a citizen of the United States, residing at Utica, in the county of Oneida and State of New York, have invented certain new and useful Improvements in Firearms, of which the following is a specification.

This invention relates to that class of firearms in which the forces incident to explosion of the charge are utilized to open the breech, extract the spent shell, introduce a fresh cartridge and cock the piece.

The present invention contemplates certain improvements, herein illustrated in a gun of the pistol type, having for their objects to increase the efficiency of the arm, simplify its construction, facilitate the assembling and disassembling of the parts, and render it safe to handle and reliable.

20 One salient feature of the improved arm consists in a novel means for postponing the opening movement of the element movable to open or close the breech until a suitable time after the inception of the action of 25 the explosion-pressure to project the bullet or projectile—for instance, in accordance with the usual object, until after the bullet or projectile has cleared the barrel and the force remaining available for opening the breech is the force of recoil.

Another salient feature consists in certain arrangements and constructions of parts whereby assembling and disassembling are facilitated and the mechanism at the same 35 time simplified and rendered substantial and durable.

Another prominent feature consists in an improved arrangement and construction of the parts involved in the mechanism for firing the charge, whereby their proper operations are assured and the element of reliability in respect to them increased.

Another important feature consists in certain novel means whereby the arm is 45 rendered safe when not in use.

Referring, now, to the accompanying drawings fully illustrative of the improved arm, Figure 1 is a side elevation thereof, showing the near grip plate partly withdrawn; Fig. 2 is a side elevation, partly in section, showing the breech-slide retracted and illustrating the disassembling operation, a certain block 15 being removed; Fig. 3 is a longitudinal vertical sectional view of the

arm with the parts shown in condition for firing, the magazine being omitted; Fig. 4 is a similar sectional view of the arm after firing, showing the trigger mechanism retracted and the breech-slide in its rearward position; Fig. 5 is a rear elevation and Fig. 6 a front elevation of the arm; Fig. 7 is a right side elevation of the arm with the breech-slide removed and the near grip plate partly withdrawn; Fig. 8 is an underneath plan of the frame, Figs. 9 and 10 showing, 65 respectively, the left hand and right hand grip plates in inside and edge elevation; Fig. 11 is a plan, partly in section, of the frame and the parts carried thereby not including the breech-slide, the sear and the 70 block 15; Fig. 11^a is a sectional view on line $v-v$, Fig. 11; Figs. 12 and 13 are sectional views on substantially the lines $w-w$ and $x-x$ of Fig. 1; Figs. 14 and 15 are top and underneath plans of the breech-bolt; Fig. 16 75 is a front elevation and Figs. 17 and 18 sectional views on the lines $y-y$ and $z-z$, respectively, of Fig. 14, looking rearwardly; Figs. 19 and 20 are plan and front elevations of the said block 15; Fig. 21 shows the 80 firing pin spring-device or driver; Fig. 22 is a plan of the dog for blocking rearward movement of the breech-slide following explosion; Figs. 23 and 24 are a side elevation and a plan of the trigger mechanism; Figs. 85 25 and 26 are a side elevation and a plan of the sear; Fig. 27 is a detail illustrating the manner of retaining in place certain longitudinally entered pins; Fig. 28 is a sectional view of the arm, illustrating the means for 90 automatically locking back the breech-slide when the last cartridge is fired; Figs. 29, 30 and 31 are a fragmentary side elevation, a plan and a rear elevation of the magazine, Fig. 30 including a part of the means shown 95 in Fig. 28; and Figs. 32 and 33 illustrate a modification of the gun.

1 is a frame having a grip 2 to receive the magazine 3, and a trigger guard 4, and formed along its upper straight edges with lateral grooves 5, such frame including a horizontally bored upwardly projecting abutment 6 receiving the barrel 7 removably secured therein, as by a pin 8 (Fig. 2). The breech-slide includes the breech-block 9, formed arched from its rearward end to a point coinciding, in the normal position of the breech-slide, with the forward

extremity of the frame, the forward portion of said breech-block being cylindrical and telescoped with the barrel; said breech-slide also includes, fitted snugly into the rear part 5 of the breech-block, the breech-bolt 10 which, without at this time describing the details thereof, has on the top a tenon 11 received in a mortise 12 in the breech-block, which tenon may form one of the sights. 10 The breech-bolt, in the normal position of the breech-slide, is supported by surfaces 13 on the top of the frame, which surfaces at 13', Figs. 11 and 11^a, are inclined downwardly at the rear, allowing the rear end 15 of the breech-bolt, when the breech-slide is retracted, to fall sufficiently to clear the tenon from the mortise for the purpose of removing the breech-bolt from the slide in the operation of disassembling the gun 20 (Fig. 2); normally, however, the upper portion (into which the rear end of the breech-bolt may drop as just stated), of a T-shaped recess 14 formed in the back upper part of the frame is occupied by a T-shaped retaining block 15 (Figs. 3, 5, 19 and 20) held in place by a pin 16 (Fig. 3), so that the breech-bolt in the action of the piece is confined to a perfect rectilinear movement. A 25 spring 17, housed in the slide, coiled about the barrel and confined between an interior shoulder 18 (Fig. 3) of the breech-block and abutment 6, normally holds the breech-slide at its forward limit of movement—with the breech-bolt against the abutment; the rearward movement of the breech-slide is limited 30 by contact of the forward cylindrical portion of the breech-block with said abutment. Having removed the pin 16 and thereupon the block 15 and then forced the breech-slide back to its rearward position, the interlock 11—12 between the breech-block and breech-bolt may be disestablished and upon the removal of the latter the breech-block and spring 17 may be slipped 35 forward off the frame and barrel, respectively.

For postponing the opening movement of the breech-slide until after the bullet or projectile has left the barrel, so that the force 40 remaining available for effecting such movement shall be the force of recoil I employ the following means, at once simple, reliable and otherwise perfectly adapted to the end in view: The rear end of the forward cylindrical portion of the breech-block has beneath the barrel an abutment-surface 19 against which bears an abutment-surface 20 at the forward end of a dog or lever 21 fulcrumed on a pin 22 in the recess 23 in the 45 frame and having its rear end exposed at the top of the loop of the trigger-guard; either or both of the surfaces 20 are inclined rearwardly with respect to the path of movement of the breech-slide, and in the 50 normal position of the parts (Fig. 3) the

dog is held up to its work, with its abutment-surface 20 bearing against the abutment-surface 19, by the spiral spring 24, backed by the adjusting screw 25, so that resistance is normally opposed to the rearward movement of the breech-slide. Such resistance, effective for a suitable time after explosion of the cartridge, ultimately ceases because, one or both of the surfaces being inclined, the backwardly influenced breech-slide operates to wipe down the forward end of the dog. The duration of this resistance is variable, depending upon the friction developed between the surfaces 19 20 (in turn depending upon the degree of obliquity of one or both of said surfaces) with a charge of a definite driving power and a definite resistance to displacement offered by the dog backed by its adjustable spring 24, and upon the extent to which the dog must move to clear the breech-block; the degree of obliquity of one or both of the surfaces 19 20 and the extent of movement of the dog being fixed upon at the time the gun is made, the precise time during which the resistance 90 is to be effective for a charge of a given driving power may be nicely determined by adjustment of the screw 25. The rear end of the dog projects into the loop of the trigger-guard so that the dog may be conveniently moved by the finger out of blocking relation to the breech-block upon manually forcing back the latter. 95

The breech-bolt has extending from its rear end a bore 26 closed at the front end 100 of the bolt excepting for a hole 27 through which the point of the firing pin 28, having movement in and longitudinally of said bore, may protrude to strike the cartridge; coextensive with this bore is a downwardly 105 opening slot 29 which receives the cocking lug 30 of the firing pin and so keeps the latter against rotation. The firing pin is backed by a driver consisting of a pin 31 having a head on its forward end, which is 110 received by a rearwardly open socket in the firing pin, and a spiral spring 32 coiled about the pin and held under compression between the head thereof and the abutment 33 forming the closed end of the socket of 115 a horizontally socketed head 34 upstanding from the block 15, it being noted that the ends of the spring are housed in the socketed firing pin and head 34. The pin 31 not only preserves the spring against buckling but adds striking mass to the firing pin, as will be obvious. Extending a suitable distance back from its forward end and on the under side thereof the breech-bolt is formed with grooves 35 receiving lateral lips (to be referred to) forming the terminals of the magazine. The empty shells are ejected upwardly upon rearward movement of the bolt, through the ejection opening 36 in the breech-slide, under the forward pressure 120 125

of the protruding firing pin coating with the extractor-hook 37 carried by the breech-bolt.

The sear 38 is formed part loop-shaped 5 in plan to permit the unobstructed elevation of the cartridges into alignment with the barrel for breeching, in fact embracing the upper end of the magazine. On each side it has a trunnion 39 which seats in bearings 40 in the top of the frame; the bearings 40 are open to permit the ready removal of the sear upon removal of the breech-slide, the edges of whose breech-block afford a 10 sliding bearing for said trunnions, confining the sear to only pivotal movement. The rear end of the sear has a rearwardly projecting lug 41 received by slot 29 in the breech-bolt and normally uplifted, so as to lock back the firing pin by engaging with 15 its lug 30, by a pin 42 projecting downwardly (for a purpose to be explained) through a housing 43 in the frame and itself pressed upwardly by a spiral spring 44 interposed between the head of said pin 20 and the bottom of the housing. The sear has a forward lug 45 and a downwardly depending arm 46.

The trigger 47 has its forwardly projecting upper end fulcrumed on the pin 48 and 30 is held in the rest position, with said end abutting the forward surface of the trigger-housing 49, by the spring 50. Housed in the back of the trigger and pivoted therein on the pin 51 is a bell-crank pawl 52 normally held by a spring 53, engaging its upright arm 52', with its forwardly extending arm 52'' bearing against the trigger, in which position the upper end of said arm 52' takes under the lug 45 on the sear. When 35 the trigger is retracted and the lower end of the pawl therefore moves in a generally upward-backward direction, the pawl arm 52', by engagement with the lug 45 of the sear, trips the latter out of engagement with the firing pin; the engagement of the pawl arm 52' with the lug 45 is of a "slip-off" character, so that when, due to the contact of the knee or lug 54 of the pawl with the arm 46 of the sear (whereby a fulcrum for the 40 pawl on the sear is afforded), the pawl is rocked forwardly on its pivot in the trigger, substantially at the time the sear clears the firing pin the pawl arm 52' clears said lug, leaving the sear free to retard the firing pin upon the ensuing recoil of the breech-slide. Fig. 4 shows the positions of the pawl and sear in the retracted position of the trigger. When the trigger is released, the movement incidentally imparted thereby to the pawl, with the co-action of spring 53, resets the pawl in re-engagement with the sear, as shown in Fig. 3.

The magazine 3, entered from below into 65 the grip 2 in the usual way and provided

with the spring-elevated platform 55, has its inwardly bent lateral lips or extensions 56 formed at the rear and on the inside with forwardly inclined flanges or ribs 57 (Figs. 4 and 29 to 31). The forward pitch of 70 magazines of this character is such that in the consequent stepped disposition of the cartridges therein (Fig. 4) the rim of the topmost cartridge registers with the cannelure of the next, in consequence of which 75 the first sometimes interlocks with the second and refuses to respond to the breeching pressure of the bolt. By providing the forwardly inclined ribs 57, the topmost cartridge under the pressure of the platform is advanced (by wiping contact of its rim with 80 said ribs) sufficiently to bring its rim out of register with the cannelure of the next by the time it is brought to rest against the overhanging lips 56, thereby avoiding their 85 interlocking.

At the left side of the magazine there is arranged the lever 58 having a lateral stud 59 journaled in the left wall of the frame. An enlargement or head 60 at the forward 90 end of this lever is movable in a recess 61 cut in said wall downwardly from the left guiding surface for the breech-slide and formed at the outside with a milled depending thumb-piece (confining the lever in assembled relation with the wall aforesaid except said thumb-piece be elevated clear of it) 62 and a hook 63 and at the inside with the overhang or projection 64 in the path of upward movement of the part 55' of the 100 magazine platform. At a point in the left side of the breech-block adjoining the hook when the breech-slide is full back (Fig. 2) a notch 65 is formed in the breech-block, being adapted to receive the hook. When, 105 therefore, the platform rises to elevate the last cartridge into alignment with the barrel, the part 55' thereof comes into engagement with the overhang 64, elevating the forward end of the lever 58 so that, upon 110 the firing of such cartridge and consequent driving back of the breech-slide, the hook of said lever will be caused to catch in the notch 65 and lock back the breech-slide, thus signifying that the magazine is empty. 115 Having replaced the empty magazine with a charged one, a downward pressure of the thumb on button 62 will allow the spring 17 to return the breech-slide, breeching a cartridge and cocking the piece. To insure 120 against premature locking action of lever 58 it is normally held with its hook-end depressed by a spring-device 66 (weaker than the platform spring) housed in the frame under its rear end.

In the rear upper part of the frame is journaled a spindle 67 having on the left side of the gun a handle 68 formed with a milled head and normally movable through approximately 90° from a position where its 130

handle projects downwardly ("unsafe") to a position where said handle projects rearwardly ("safe"). The spindle receives the rear end of lever 58 in a transverse saw-cut 5 or groove 69 extending only part way around the spindle and formed deeper at one point than elsewhere, producing an angular cam 70 which, with the spindle in the position shown in Fig. 1 and the breech-10 slide in the position shown in Fig. 4, operates to hold the lever in locking engagement with the breech-slide with its hook in the notch 65 thereof (as when, having manually retracted the slide, it is desired to lock it back), but which, with the spindle in the position shown in Fig. 2, leaves the lever depressed. In the vertical plane of the lug 41 of the sear the spindle has a saw-cut or recess 71 disposed so as to register with the 15 lug (allowing movement of the sear on its fulcrum) when the spindle is in the position shown in Figs. 2 and 28; when the spindle is in the position shown in Fig. 1 the uncut surface of the spindle underlies the sear lug 20 41 and prevents movement of the sear. Since movement of the spindle from unsafe to safe involves movement of lever 58 toward its position for interlocking with the breech-slide in the closed position (Fig. 1), the 25 breech-slide has a recess 72 affording the necessary clearance to hook 63 and overhang 64; the lever 58 cannot lock the breech-slide against the desired backward movement upon explosion of the last cartridge, 30 due to a premature upward pressure thereon by the platform part 55', because the latter is suitably depressed relatively to the remainder of the platform which is at that time held down by the breech-slide.

35 40 The spindle is longitudinally removable from the frame, being normally retained by a suitably housed spring-pressed plunger 73 taking into a groove extending only part way around the spindle, forming an angular 45 cam 74 and disposed on the same side of the spindle as groove 69; thus, when the spindle is between or at either of the "safe" and "unsafe" positions, it cannot be removed, but when turned beyond these limits (the 50 breech-block being removed) it can be, parts 73 and 58 now engaging smooth or un-grooved portions thereof. It will be understood that in the assembled condition of the gun the breech-block and the left grip plate 55 (81) confine the handle (and hence the spindle) to its aforesaid 90° of movement; also that cams 70 and 74, being angular, are 55 responsible for their respective co-operating parts 58 and 73 holding the spindle at either the one or the other of its limits of movement.

To lock the sear against releasing movement except when the gun is gripped for firing a safety lever 75 is pivoted at its lower 60 end and partly housed in the rear of the

grip, being normally pressed rearwardly by a spring 76 to a limit afforded by its lug 77 abutting a part of the frame, in which position a projection 78 thereon underlies the pin 42 and so prevents depression of the rear end of the sear. When the gun is properly gripped for firing, the lever may be shifted forward until its projection clears the pin, leaving the latter and hence the sear free to descend in response to actuation from the trigger mechanism.

Certain pins, for instance 16 and 48, are held against longitudinal displacement in the novel manner shown in Fig. 27. The pin and the bore formed in the frame to receive it have registering channels 79 forming cam-shoulders extending more or less clear around the pin, and in these is fitted a split ring 80 normally serving as a key to block the withdrawal of the pin except when force is exerted on the pin sufficient to wipe the ring out of one channel into the other, involving a change in its diameter (in the present instance, a collapse of the ring).

The grip plates 81 have on their inner sides dovetailed tongues 82, enabling them to be fitted to or withdrawn from the frame by sliding movement in an up or down direction. They may be entered from below or above, as shown in the drawings for the sake of illustration. Thus, in Fig. 1 the near grip-plate is entered from below and comes to rest against the stop 83 formed by a part of the frame, being held in position by the dowel pin 84; in Fig. 2 the near grip-plate is entered from above (with the breech-slide removed) and comes to rest against the stop 85, being held down by the breech-slide when the gun is assembled.

To indicate the presence or absence of a cartridge in the breech I provide the breech-block with the inwardly bent spring 86 having the outwardly projecting stud 87 and fitted to the inside of said breech-block over the extractor 87, its stud being received by the opening 88 in the breech-block. If a cartridge is present in the breech the extractor will be elevated and hence will elevate the spring 86 so that its stud protrudes and may be felt by the operator's thumb; if no cartridge is present the stud remains retracted.

Operation: Assuming the gun to be cocked (Fig. 3) and the magazine containing cartridges, when the trigger is pulled the sear 120 is tilted to release the firing pin which then strikes and explodes the cartridge (previously breeched by manually retracting the breech-slide to allow said cartridge to be elevated by the platform of the magazine 125 into alignment with the breech, Fig. 4, and then permitting spring 17 to return the breech-slide to breech-closing position), the resulting recoil of the breech-slide and subsequent return to breech-closing position in-

volving the ejection of the empty shell through opening 36 and the recocking of the piece, as well as the breeching of the next cartridge in the magazine, all in general the same as in other guns of this type; if no cartridge remains in the magazine the breech-slide will be locked back upon recoil in the way already explained, whereupon the empty magazine is withdrawn, a filled one introduced and the lever 58 then manually depressed to allow the breech-slide to assume the breech-closing position, breeching the topmost cartridge and leaving the firing pin cocked.

In the gun illustrated in Figs. 32 and 33 the lever 88, corresponding to lever 58 already described in the function of locking the breech-slide in its rearward position in the manual performance of this operation, is pivoted in a recess 89 in the block 15, its hooked end being normally held depressed by the spring 90. The spindle 91, corresponding in the function of locking the sear with the spindle 67 already described, and for that purpose having the sear-liberating recess 92, has a saw-cut or groove, formed deeper at one point than elsewhere, which groove (93) receives the hooked end of said lever. When the handle 94 of said spindle is in any position between and including its downwardly or rearwardly projecting positions it is locked by said lever against removal, (said lever being in turn confined by one side of the recess 89 and the opposite wall of the gun-frame against lateral displacement); when the spindle is turned to any other position, as by having first removed the breech-slide, it may be withdrawn without obstruction. The groove 93 forms a cam in the spindle which, when its handle occupies the position shown in Fig. 32 ("unsafe"), permits the lever to stand depressed but which, when the handle is turned to the rearward position ("safe"), holds the lever elevated, its hook being either received (idly) in recess 95 in the breech-slide or, the breech-slide having been manually forced back, engaging in the notch 96 therein and maintaining the breech-slide in the rearward position. In this instance, the grip plates 97 (having tongue and groove connections with the frame the same as in the gun first described), entered into position from above when the breechblock is removed, are held against vertical displacement by the spindle.

Having thus fully described my invention, what I claim and desire to secure by Letters Patent is:

1. A gun including a frame, a barrel member, a breech-closing member, one of said members being movable into and out of breech-closing relation to the other, and mechanism for firing the charge including a trigger, in combination with means for re-

tarding the breech-opening movement of the movable member upon firing the charge projecting into proximity to the trigger and operable by the trigger-finger of the operator.

2. A gun including a sliding member and a breech-bolt member movable together longitudinally of the gun and having an interlock separable by movement of the bolt member crosswise of their path of sliding movement, and guiding means for said members comprising the bolt member against crosswise movement and having a part of its guiding portion removable to allow such movement when said members are at a definite point in their sliding movement.

3. A gun including a sliding member and a breech-bolt member movable together longitudinally of the gun and having an interlock separable by movement of the bolt member downwardly, and means to confine the bolt member against downward movement having a part of its guiding portion removable to allow such movement when said members are at a definite point in their sliding movement.

4. A gun including a sliding member and a breech-bolt member movable together longitudinally of the gun and having an interlock separable by movement of the bolt member crosswise of their path of sliding movement, and means to confine the bolt member against crosswise movement having a part of its guiding portion removable to allow such movement when said members are at the rearward point in their sliding movement.

5. A gun including a sliding member and a breech-bolt member movable together longitudinally of the gun and having an interlock separable by movement of the bolt member downwardly, and means to confine the bolt member against downward movement having a fixed forward portion extending only part way back of the forward end of the bolt member when said members are at their rearward limit of sliding movement and a removable rearward portion, whereby, upon removal of said rearward portion, said bolt member in the retracted position may be canted downwardly on said forward portion as a fulcrum to separate said interlock.

6. A gun including, with a firing mechanism, a sliding member and a breech-bolt member movable together longitudinally of the gun and having an interlock separable by movement of the bolt member crosswise of their path of sliding movement, and means to confine the bolt member against crosswise movement having a part thereof removable to allow such movement when said members are at a definite point in their sliding movement and affording partial support to the firing mechanism.

7. A gun including a sliding member having a rearward bolt-receiving portion and a breech-bolt underlying said portion, said members having an interlock separable by downward movement of the bolt member, and guiding means for said members, confining the bolt member against downward movement and having a part of its guiding portion removable to allow downward removal of the bolt member from the sliding member.
8. A gun including, with the firing mechanism, a sliding member having a rearward bolt-receiving portion and a breech-bolt underlying said portion, said members having an interlock separable by downward movement of the bolt member, and guiding means for said members, confining the bolt member against downward movement and having a part of its guiding portion removable to allow downward removal of the bolt member from the sliding member and affording partial support to the firing mechanism.
9. In combination, a frame, a rearwardly sliding member guided thereon and having a rearward bolt-receiving portion movable into rearwardly projecting relation to the frame, and a bolt member underlying said portion, said members having an interlock separable by downward movement of the bolt member and said frame supporting the bolt member and having a part thereof removable to allow downward movement of the bolt member in the rearward position thereof.
10. A gun including a sliding member having a rearward downwardly open arched portion and a breech-bolt member entered from below into said arched portion, said members having an interlock holding them against relative longitudinal movement and being separable by downward movement of the bolt member, and means, confining the bolt member against downward movement, for guiding the sliding member.
11. In combination, the frame having an upstanding barrel-abutment, the breech-block longitudinally movable on and guided by the frame and having a rearward downwardly open arched portion housing said abutment, a breech-bolt entered from below into said arched portion and disposed therein back of the abutment, said block and bolt having a mortise and tenon connection separable by downward movement of the bolt, a spring interposed between a part of the frame and the block and holding the latter forward with the bolt abutting the abutment, and mechanism for firing the charge, said frame confining the bolt against downward movement and having a part thereof removable to allow removal of the bolt.
12. In combination, the frame having an upstanding barrel-abutment, the breech-
- block longitudinally movable on and guided by the frame and having a rearward downwardly open arched portion housing the abutment, a breech bolt housed and removably held in said arched portion back of the abutment and removable downwardly from said arched portion, means normally holding the breech-block forward with the breech bolt abutting the abutment, and mechanism for firing the charge, the frame confining the breech-bolt in said arched portion of the breech-block.
13. A gun including the frame, a longitudinally movable breech-slide, a cockable firing device adapted to be moved to cocked position by the breech-slide and means for releasably sustaining said device in cocked position including a sear having a bearing in the frame and removable in an upward direction from its bearing and confined normally against such removal by the breech-slide.
14. A gun including a frame, a longitudinally movable breech-slide, a cockable firing device adapted to be moved to cocked position by the breech-slide and means for releasably sustaining said device in cocked position, including a sear having a sliding bearing upon the breech-slide.
15. The combination of the frame, a recoil breech-slide, a cockable firing device adapted to be moved to cocked position by the breech-slide, a sear for the firing device normally held in position to dog the firing device, and means for effecting releasing movement of the sear having at one point thereof a slip-off engagement with the sear and at another point thereof a fulcrum on the sear.
16. The combination of the frame, a recoil breech-slide, a cockable firing device adapted to be moved to cocked position by the breech-slide, a sear for the firing device normally held in position to dog the firing device, a trigger, and a device for transmitting motion from the trigger to the sear having at one point thereof a slip-off engagement with the sear and at another point thereof a fulcrum upon the sear.
17. The combination of the frame, a recoil breech-slide, a cockable firing device adapted to be moved to cocked position by the breech-slide, a sear for the firing device normally held in position to dog the firing device, a trigger, and a pawl for transmitting motion from the trigger to the sear pivoted in the trigger and having at one point thereof a slip-off engagement with the sear and between its pivot and the first-named point a fulcrum on the sear.
18. The combination of the frame, a recoil breech-slide, a cockable firing device adapted to be moved to cocked position by the breech-slide, a sear for the firing device movable up and down and normally held

in position to dog the firing device, a trigger pivoted in the frame forward of the sear, and a forwardly yielding pawl supported on the trigger and substantially over its point of support on the trigger having a slip-off contact with the sear and between said point and the point of contact with the sear having a fulcrum on the latter, said sear having a forwardly terminating surface affording said slip-off contact for the pawl.

19. In combination, the frame, a recoiling breech-slide, mechanism for firing the charge, a locking device for a part of said mechanism, a magazine having a platform normally pressed upwardly, and a platform-actuated locking device for the breech-slide operated by and upon movement of the first locking device.

20. A gun having, with mechanism for firing the charge, a controlling spindle for a part of said mechanism journaled in and removable longitudinally from the gun and having a groove extending only part way around the same, a spring-pressed retaining device engaged in said groove, and means for confining the rotary movement of the spindle within limits commensurate with the engagement of the retaining device within said groove having a part thereof removable to permit rotary movement of said spindle beyond one of said limits.

21. A gun including, with a fixed structure and a removable structure, one having

a pin-receiving bore, a pin for retaining the removable structure in place in the fixed structure fitted into said bore and a yielding split-ring embracing the pin, said pin and the bore having shoulders extending around the pin and normally engaged by said device and coacting to prevent longitudinal displacement thereof, one of said shoulders constituting a cam and serving, upon sufficient pressure being exerted on the pin to move the same endwise, to clear said device from engagement therewith and allow removal of the pin.

22. A gun including the frame having a depending grip, firing mechanism having a firing device, a sear for the firing device movable at its rear portion downwardly to release the firing device, a trigger for the sear, a spring-elevated device normally holding elevated the rear portion of the sear, and a normally retracted lever fulcrumed in the back of the grip and having a part thereof normally underlying and blocking downward movement of the spring-elevated device and adapted to be shifted out of blocking relation to the same when the lever is moved forward upon the gun being gripped for firing.

In testimony whereof I affix my signature in presence of two witnesses.

MORRIS F. SMITH.

Witnesses:

BENJAMIN ADRIANCE,
CARLETON L. WOOD.
